[57] CLAIM

The ornamental design for a sport bag, as shown and described.

DESCRIPTION

FIG. 1 is a front view of the sport bag showing my new design;

FIG. 2 is a left side view of the sport bag shown in FIG. 1, the right side view being a mirror image of the left side view; FIG. 3 is a rear view thereof, shown with a portion of the mesh body broken away to more clearly show the internal compartment;

FIG. 4 is a top plan view thereof; and,
FIG. 5 is a bottom plan view thereof.
